GAS BURNER

Theodore H. Thiele, Milwaukee, Wis., assignor to
 A. O. Smith Corporation, Milwaukee, Wis., a
 corporation of New York

Application January 26, 1942, Serial No. 428,248

2 Claims. (Cl. 158—99)

1

This invention relates to a gas burner for operation with butane and other similar hydrocarbon fuels, and more particularly to the venturi to be employed in such burner.

One object of the present invention is to provide a gas burner with an improved venturi that effectively mixes the gas and air in their passage from the inlet end of the venturi to the burner ring.

Another object is to provide a gas burner with an improved venturi that is economical to construct.

A further object is to provide a gas burner in which the mixed gas and air is equally distributed throughout the internal channel of the burner.

Other objects will become apparent from the following description and accompanying drawing illustrating an embodiment of the invention.

In the drawing:

Figure 1 is a top plan view, partly in section, of a gas burner venturi embodying the invention;

Fig. 2 is a vertical section taken on line 2—2 of Fig. 1;

Fig. 3 is a section taken on line 3—3 of Fig. 1;

Fig. 4 is a section taken on line 4—4 of Fig. 1, and

Fig. 5 is a section taken on line 5—5 of Fig. 1.

Referring to the drawing, there is illustrated an embodiment of the invention comprising a tubular ring member 1 with an internal channel 2, cast integrally with the venturi 3 having an internal passage 4 connecting with the channel 2.

It is preferred that the ring member 1 have a substantially continuous slot 5 in its upper surface for constituting the flame propagating jet. The dead ends 6 adjoin the venturi 3, and provide a depression in the upper surface of the burner member. The internal channel 2 in the member 1 gradually decreases in cross-sectional area in its extent from the side of the burner where the gas first enters, to the opposite side.

The venturi 3 is a generally tubular shaped member of substantial length and has a bell-like inlet end 7, a constricted throat portion 8, a neck portion 9 and a flared outlet end 10. The flared outlet end 10 of the venturi is integrally cast with the ring member 1, and the baffles 11 are vertically disposed adjacent the outlet end of the venturi 3 to direct the flow of gas around the burner as it passes from the venturi 3 into the channel 2 of the tubular ring member 1.

The bell-like inlet end 7 is provided with an opening 12 for connection to a suitable supply of gas and also with the openings 13 to receive

2

the air required to provide the gas and air mixture desired.

The constricted throat portion 8 is provided in the venturi 3 at a position between that of the inlet end 7 and the neck portion 9. The throat 8 is preferably round and has only a slight longitudinal extent.

The neck 9 is disposed between the throat 8 and the outlet end 10. In contrast to the throat portion 8, the neck 9 of the venturi 3 has a non-circular shape and gradually increases in cross-sectional area from the throat 8 to the flared outlet end 10. Thus the passage 4 in the venturi 3 at the neck portion 9 and the outlet end 10 is non-circular in shape. Figures 3 and 4 illustrate the progressive increase in cross-sectional area in the venturi, Fig. 3 showing the cross-sectional area of the venturi 3 at the throat 8 and Fig. 4 indicating the increased area of the venturi at the outlet end 10. This increase in cross-sectional area from the throat 8 to a point about three inches from it is preferably not greater than 50% and in the burner illustrated the outlet end 10 has an area only about 20% greater than the cross-sectional area of the throat.

This gradual increase in cross-sectional area in the venturi is preferably obtained by directing the lower portion of the venturi downwardly from the horizontal in its extent between the throat 8 and the outlet end 10. The efficiency of the mixing of the fuel with air is increased by this manner of construction over a construction strictly horizontal or upwardly inclined. The downward slope of the venturi directs the fuel forwardly to thereby prevent any escape of the gas in the fuel mixture through the openings 13 by which the primary air is supplied in the event that the gas tends to settle to the bottom of the venturi.

In the embodiment of the invention illustrated the non-circular neck 9 graduates into the outlet end 10, the latter being shaped in the form of a rectangle. Although a rectangular shape in the outlet end 10 is preferred, it is not necessary that the outlet end be rectangular as other elongated or irregular shapes may be effectively employed. The outlet end should have its major axis vertical and its minor axis horizontal and the length of the major axis should be at least one and one-half times the minor axis.

The particular shape of the venturi with the accompanied increase in cross-sectional area of the passage 4 as described, combines with the round constricted throat portion 8 to produce

eddy currents that increase the uniformity of the gas and air mixture and prevent any formation of globules of the burner fuel with either a greater or less proportion of air or gas than that of the normal flowing fuel. In a burner where butane gas is employed, the butane being heavier than the air with which it is mixed has a tendency to settle out instead of readily mixing with the air. The employment of the venturi described in a gas burner supplied with butane prevents the butane from settling in this manner.

Through the openings 13 in the inlet end 7 of the venturi, the round constricted throat 8 siphons the primary air required to be mixed with the gas and directs the eddy currents of gas and air generated in the venturi toward the ring of the burner. This action of the throat 8 combines with the downward slope of the venturi, previously described, to prevent the fuel from flowing backwards toward the inlet end of the venturi.

In the operation of the burner described, gas is forced into the center opening 12 of the inlet end 7 of the venturi 3 by operation of a valve not shown. As the gas reaches the throat 8, a suitable supply of air is automatically siphoned through openings 13 provided in the inlet end 7 by operation of the round constricted throat 8.

As the mixture of gas and air flowing in the venturi reaches the neck 9, eddy currents are produced as the non-circular cross-sectional area of the passage 4 in the neck 9 progressively increases in the travel of the gas mixture toward the outlet end 10.

As the eddy currents of gas and air flowing in the passage 4 of the venturi 3 strike the segment 14 disposed at the outlet end 10 of the venturi, the fuel is deflected laterally in opposite directions in a uniform manner and flows from the passage 4 into the connecting channel 2 of the burner ring member 1 on either side. The flowing fuel enters the channel 2 at the lowest point in the burner and the lateral ring deflectors or baffles 11 direct the flow of the fuel around the

burner so that the fuel will be equally distributed throughout.

The effect of the present invention is to provide a gas burner that produces and employs a well-mixed equally distributed fuel that is an improvement over burner fuels previously known.

Various embodiments of the invention may be employed within the scope of the accompanying claims:

10 I claim:

1. In a gas burner, a Venturi supply tube having an inlet end with a constricted throat portion of circular cross section, and the section of the tube between the throat and burner being of gradually increasing cross-sectional area with the upper wall extending substantially parallel to the horizontal axis of the tube and with the lower wall of the tube extending downwardly from the throat at a substantial angle to provide for the increase in cross-sectional area, the width of said tube section being not greater than the diameter of the throat and the cross-sectional area at approximately three inches from the throat being not more than one hundred fifty percent as great as that of the throat portion of the tube.

2. A gas burner comprising a circular tubular ring member having jet means provided in its upper surface for the discharge of gas therefrom throughout substantially the entire circumference of the ring, a Venturi supply pipe extending radially to one side of the burner ring in a plane below the horizontal plane of the ring to discharge gas into the ring at the bottom of the latter and in a direction laterally and upwardly from said supply pipe, a portion of the upper surface of said ring being depressed to the level of said supply pipe immediately above the same to direct the gas laterally to opposite sides of the pipe and being imperforate to eliminate flame propagation immediately above the supply pipe.
